NORMAN HUBBARD, OF ELIZABETH, NEW JERSEY, ASSIGNOR TO THE BABCOCK & WILCOX COMPANY, OF BAYONNE, NEW JERSEY, A CORPORATION OF NEW JERSEY.

BOILER BAFFLE.

Application filed August 3, 1922. Serial No. 579,507.

My present invention relates to boiler walls or baffles particularly of the type in which the baffle extends longitudinally of a row of water tubes or the like and will best be understood from the following description and the appended drawings, in which Fig. 1 is a portion of a known type of boiler, embodying one application of my invention to form a baffle on the lower row of tubes, 10 a partial longitudinal section of the baffle being taken on the line 1—1 of Fig. 3; Fig. 2 is a perspective of the two elements which constitute a unit in the illustrative form of baffle; Fig. 3 is a cross-section of the illustrative form of baffle, showing the manner in which it may be removed or installed; Figs. 4, 5, 6, 7, 8 and 9 are, respectively, side and end elevations of variations in the length and shape of the two elements to accommodate them to various conditions met with in practice.

Like reference characters indicate like parts in the several views.

In the illustrative form of my invention, the baffle is made up of a plurality of units, each composed of a member which I have termed the hook member and the other the filling piece. The hook member is curved to a radius of the boiler tube, as shown at 10, 25 in an arc, in the illustrative form, of approximately 120°, and is straight from a tangent with the horizontal center line of the tube to a point just inside the bottom of the tube, as shown at 12, and thence, in the 30 illustrative form, is flared out equally, on both sides at its other end, as shown at 13 and 14.

The filling member 15, in cross-section, has sloping sides corresponding to the sloped sides 13 and 14 of the hook member. The width and height of the wedge member is such that it may be inserted between two of the hook members suspended on two adjacent boiler tubes, with its upper surface in contact with the bottom of one of the boiler tubes, and, upon being released, will fall by gravity to a position where its lower or narrow face is in line with the bottoms of the hook members. In this manner a number of the filling members, alternating with an equal number of hook members, will form a continuous wall or baffle on one side, or beneath a row of boiler tubes.

By making hook members extending between adjacent tubes of a uniform thickness

equal to the space between tubes, less only necessary clearance, their strength is more than double that of any arrangement contemplating two or more adjacent members occupying space between tubes, for the reason that the latter, if duplicates, could in no case have a thickness equal to half the width of space between tubes.

The baffle may be extended around curved portions of the tubes, as illustrated in Fig. 1. This may be accomplished by the form of hook member and filling piece shown in Figs. 6 to 9, inclusive, the hook portion being curved preferably on the top only to fit in between the next adjacent row of tubes 60 of the boiler, the lower face of the body portion preferably being similarly curved (see Fig. 6) while the inside portion of the hook which fits on the tube may be made as a cylindrical opening so that the hook contacts with the tube only at the opposite ends of the piece. Similarly the filling piece 15 may have its lower surface curved to adapt it to a curved surface for the face of the baffle at 65 that point. At other portions of the baffle, instead of curving the hook portion 10, the ends of the hook member and the filling piece may be angled as shown best in Fig. 4.

The advantages of my arrangement will be obvious to those skilled in the art. A baffle may be readily built up which will extend longitudinally of the water tubes and the parts of which will have considerable strength. For instance, the straight portion 12 may have a thickness almost as great 70 as the distance between the water tubes. Moreover, the baffle may be readily built up and will not fall to pieces, the sloping sides of the filling piece 15 being such that when the filling pieces are supported on the hook members, the filling piece may move downward by gravity until wedged between the adjacent walls of a pair of body portions 11. Similarly, any portion of the baffle may be 75 readily removed in the manner shown in Fig. 3. The filling pieces for two or more hook members on adjacent tubes will be first removed and then the hook members may be swung as indicated in Fig. 3, so that one 80 of the hook members, after completing its rotation around the axis of its tube, may be withdrawn through the space between the tubes. By attaching a baffle to a row of tubes by means of hook members of uniform 85 thickness, only one of which hook members

100

- occupies a space between adjacent tubes and partially encircles one tube, there can be no fusion of the baffle members that would lock them between the tubes and such as occurs in the case of two hook or wedge members occupying the space between two tubes and contacting with two tubes instead of one, removal and replacement of baffle is greatly facilitated.
- 10 While, preferably, I make the side walls 13, 14 sloping so that the filling piece may wedge itself between them and produce a tight fit by taking up any inequalities due to manufacture, nevertheless, if desired, the 15 cooperating faces between the filling pieces and the body portions may be of any other suitable form, as for instance, stepped so that a projecting ledge on 15 will extend over a corresponding ledge on the body portion 20 of the hook member.
- It will be understood that the form shown is merely illustrative and that the embodiment of my invention may be widely varied.
- I claim:—
- 25 1. In a boiler having tubes, a wall comprising a plurality of hook members each having a hook portion arranged to extend between a pair of tubes and partially around one of them, and a body portion at the side 30 opposite the hook portion, and a plurality of filling pieces adapted to fit between the body portions of adjacent hook members and form with said body portions a substantially continuous wall surface, one hook member only being located between adjacent 35 tubes and with the end of the hook portion free.
2. In a boiler having tubes, longitudinal baffle comprising a plurality of hook members each having a hook portion arranged to extend between a pair of tubes and partially around one of them, a body portion at the side opposite the hook portion, and a plurality of filling pieces adapted to fit between the body portions of adjacent hook members and form with said body portions a substantially continuous baffle surface the sides of said body portions and of said filling pieces being interlocked to prevent motion of the filling pieces in a direction away from the tubes, one hook member only being located between adjacent tubes and with the end of the hook portion free.
3. In a boiler having tubes, a longitudinal baffle comprising a plurality of hook members each having a hook portion arranged to extend between a pair of tubes and partially around one of them, a body portion at the side opposite the hook portion, and a plurality of filling pieces adapted to fit between the body portions of adjacent hook members and form with said body portions a substantially continuous baffle surface, the sides of said body portions and of said filling pieces being reversely sloped to prevent motion of the filling pieces in a direction away from the tubes, one hook member only being located between adjacent tubes and with the end of the hook portion free.
4. In a longitudinal baffle for a series of spaced parallel tubes, a hook member having a body portion trapezoidal in cross-section and a hook integral with the body portion and adapted to extend through the space between a pair of tubes and partially around one of them, the wider part of the trapezoid being farthest away from the hook, and a filling piece, trapezoidal in cross-section and adapted to fit between the sides of the body portions of a pair of adjacent hook members.
5. In a longitudinal baffle for a series of spaced parallel tubes, a hook member having a body portion trapezoidal in cross-section and a hook integral with the body portion and adapted to extend through the space between a pair of tubes and partially around one of them, the wider part of the trapezoid being farthest away from the hook, and a filling piece, trapezoidal in cross-section and adapted to fit between the sides of the body portions of a pair of adjacent hook members.
6. In a longitudinal baffle for a series of spaced parallel tubes, a hook member having a curved portion adapted to partially surround a tube, a straight portion connected to the curved portion and adapted to extend between a pair of tubes, and a body portion connected to the straight portion, the several portions being constructed and arranged to permit said curved portion to be passed through the space between a pair of tubes and rotated on a tube to bring said straight portion in the space between the tubes with the body portion opposite such space, the sides of the body portion being adapted to cooperate with the sides of the body portions of an adjacent hook member, to support filling pieces near the tubes, and filling pieces adapted to cooperate with said body portions.
7. In a baffle for a series of spaced tubes, members passing between the tubes and each formed at its upper end with a hook adapted to engage the upper side of one of said tubes and at its other end and beneath the tubes thickened by flaring the same outwardly, and filling pieces adapted to fit between the flared ends of said first named members and thereby lock the same in position on the tubes, and forming therewith a baffle with a substantially continuous wall on one side.
8. In a baffle for a series of spaced tubes,

members passing between the tubes and each formed at its upper end with a hook adapted to engage the upper side of one of said tubes and at its other end and beneath the tubes thickened by flaring the same outwardly, and filling pieces adapted to fit between the flared ends of said first named members and thereby lock the same in position on the tubes, and forming therewith a baffle with a substantially continuous wall on one side, the filling pieces being held in position by gravity.

9. In combination, a row of tubes and a baffle supported thereon, said baffle comprising hook members extending between the tubes and each having at one end a hook portion extending partially around a tube, and filling pieces between and engaging the other ends of adjacent hook members and forming therewith a permanent structure supported by said hook portions, and filling pieces located between adjacent tiles for securing them in position on the tubes.

10. In combination, a row of tubes and a baffle supported thereon, said baffle comprising hook members extending between the tubes and each having at one end a hook portion extending partially around a tube and suspended therefrom, the opposite ends of said hook members being flared away from the tubes, and filling pieces having flared sides engaging the flared sides of the hook members, the filling pieces being held in position by gravity and forming on their lower sides with the lower sides of the hook members a substantially continuous surface.

11. In combination, a row of tubes, a baffle formed of tiles supported on said tubes and comprising hook members having hook portions extending between tubes and partially around the same to support the baffle, there being but one hook member between any two adjacent tubes, and filling pieces located between adjacent tiles for securing them in position on the tubes.

NORMAN HUBBARD.
